N. SANDBERG

CARTON ROUTING MACHINE

Filed Nov. 7, 1924

Patented Aug. 18, 1925.

1,549,892

UNITED STATES PATENT OFFICE.

NELS SANDBERG, OF ST. PAUL, MINNESOTA, ASSIGNOR TO WALDORF PAPER PRODUCTS COMPANY, A CORPORATION OF MINNESOTA.

CARTON-ROUTING MACHINE.

Application filed November 7, 1924. Serial No. 748,507.

To all whom it may concern:

Be it known that I, NELS SANDBERG, a citizen of the United States, residing at St. Paul, in the county of Ramsey and State of Minnesota, have invented new and useful Improvements in a Carton-Routing Machine.

This invention relates to machines used in the manufacture of cartons for performing the operation known as routing which consists in removing or knocking out die-cut waste portions of carton blanks, preparatory to folding and securing the blanks in box form.

As is well known, it is necessary to forcibly remove certain waste portions of the blanks after the outlines of the cartons have been marked by suitable dies. Heretofore, the greater part of this routing work has been done by hand, although machines which simplify the work to a certain extent have been devised. These old machines are not efficient, however, for use in large factories where frequent adjustments must be made to adapt the machine for use upon cartons of widely differing form and it is also true that the old machines known to applicant do not afford sufficiently accurate placing of the routing elements to properly and cleanly remove some of the waste portions.

It is my object to obviate these defects by providing a machine of this kind having a series of routing elements which are independently and quickly movable to the exact positions necessary to efficiently knock out die-cut portions of cartons.

This invention also includes certain other features of construction which will be more fully pointed out in the following specification and claims.

In the accompanying drawings, I have illustrated the best form of my device at present known to me. Referring to the drawings, Figure 1 is a plan view of my machine; Fig. 2 is a fragmentary, transverse section of the same and Fig. 3 is a section through one of the routing elements and operating mechanism taken on the line 3—3 of Fig. 2.

My machine is supported in a suitable frame having end standards 4 connected by a pair of rigid, threaded rods 5 and supporting a drive shaft 6, which is parallel to the rods 5. Pivoted upon this shaft 6 is a series of routing discs 7, of like size and having blunt teeth upon their peripheries,

adapted to knock out die cut waste portions of carton blanks 3. A support 8 for each of the discs 7 is freely pivoted upon the shaft 6 and has a journal bearing for a short shaft 9, carrying the disc 7. The support 8 is a plate in the form of a segment, having arcuate slots 10, through which the rods 5 extend. Pairs of nuts 11 threaded on the rods 5 adjacent to opposite faces of each of the supports 8 are adapted to be manipulated to grip said supports and hold them in any desired arcuate positions. To severally drive the routing discs 7, I mount sprocket wheels 12 and 13 upon the shafts 6 and 9, respectively, and connect said wheels by an endless chain 14. The sprocket wheels 12 are caused to rotate with the shaft 6 by a longitudinal key 15 on said shaft, and said wheel is slidable longitudinally upon the shaft 6.

Obviously, the details of construction of the bearings at the upper and lower ends of the supports 8 may be varied without departing from the spirit of my invention, but I prefer to form each of the sprockets 12 (as shown in Fig. 3) with a long hub 15 and to place a bushing 16 between the outer periphery of said hub and the bore of the support 8. A nut 17 is provided to maintain the proper positions of the wheel 12 and bushing 16. At the lower extremity of each support 8, the routing disc 7 is secured to a flange 18 on the shaft 9, and a bushing 19 is placed between said shaft and the bore of the support 8. The sprocket 13 is rigidly secured to a threaded end 20 of the shaft 9. To drive the shaft 6, a pulley 21 is fixed upon said shaft near the outer face of one of the standards 4.

A suitable feed carriage for a stack of 95 the cartons 3 is shown in Figs. 1 and 2. Thus, a table 22 is made slidable vertically in guide ways 23. This table 22 is adapted to support a receptacle 24 for the blanks 3, the receptacle having sides 25 arranged to fit about three sides of the carton blanks, and being formed with slots 26, as shown in Fig. 1, to receive the routing discs 7. The slots 26 are disposed to register with the die cut portions to be removed from the carton blanks. Counter weights 27, provided with cables 28 passing over pulleys 29, are adapted to facilitate vertical movement of the table 22 carrying the blanks. As will be readily understood, the receptacle 24 is so 110

placed upon the table 22 that the waste portions to be removed from the carton blanks project above the several routing discs 7.

Operation.

5 The machine is prepared to operate upon cartons of a predetermined shape by first constructing a receptacle 24 having slots 26 which register with the die cut portions to be removed. The receptacle 24 is now secured upon the table 22, as shown in Fig. 2. To adjust the positions of the discs 7, the nuts 11 are loosened and rotated upon the rods 5 to carry the supports 8 longitudinally 10 upon the shaft 6. Thus, the discs 7 are moved to proper position opposite the several slots 26. Before tightening the nuts 11, the supports 8 are pivoted upon the shaft 6 to bring one of the discs 7 into each of the 15 slots 26 with the periphery of the disc extending to the innermost extremity of the waste portion to be removed. The nuts 11 are finally tightened against the faces of the supports 8 to firmly hold the routing discs 20 in operating position. When the pulley 21 is driven from a suitable source of power in the direction indicated by an arrow in Fig. 2, the shaft 6 will drive the shafts 9 through 25 the sprocket wheels 12 and 13 and chains 14. 30 A stack of the cartons to be operated upon is now placed in the receptacle 24, when the support 22 carrying said receptacle may be depressed to cause the teeth of the discs 7 to knock out the waste portions of the cartons. 35 As will now be readily understood, by making the discs 7 extensible to the innermost extremity of each portion to be knocked out, the difficulty heretofore encountered of tearing away only a part of the waste material is avoided. By making provision for 40 accurate, individual adjustment of the routing disc positions, I guard against mutilating the cartons, as frequently occurs when the routing discs are not properly placed 45 relative to the waste portions to be removed. Furthermore, the work of preparing the present machine for use upon cartons of differing shapes is greatly simplified as compared with prior machines known to applicant. I also do away with the necessity for 50 a plurality of interchangeable sets of routing discs of differing sizes.

Having described my invention what I claim as new and desire to protect by Letters Patent is:

1. In a machine of the class described, a revoluble shaft, a plurality of routing discs severally movable in arcs about said shaft, and revoluble about centers which are offset 60 from said shaft, a plurality of knocking elements formed on the periphery of each of said discs to engage and remove die-cut portions of carton blanks, means for securing the several discs in differing arcuate 65 positions relative to said shaft, and means

operatively connecting said shaft with the several routing discs.

2. In a machine of the class described, a revoluble shaft, a plurality of supports for routing discs pivoted upon said shaft, 70 routing discs severally revoluble upon said supports and offset from said shaft thereon, a plurality of knocking elements formed on the periphery of each of said discs to engage and remove die-cut portions of carton blanks, independent means for securing the several supports in differing angular positions upon said shaft, and means operatively connecting said shaft 75 with the several routing discs. 80

3. In a machine of the class described, a carriage for a plurality of carton blanks, a series of supports for routing discs severally movable toward and away from said carriage, rotating discs severally revoluble 85 upon said supports, a plurality of knocking elements formed on the periphery of each of said discs to engage and remove die-cut portions of carton blanks, means for securing the several supports in differing positions 90 relative to said carriage, and means for rotating the several routing discs on said supports. 95

4. In a machine of the class described, a frame, a shaft and a rod extending in parallel relation one to the other in said frame, a support for a routing disc pivoted upon said shaft and formed with an arcuate slot adapted to receive said rod, means disposed on said rod to engage said support, a disc 100 having peripheral teeth revolvably carried on said support, and means operatively connected to said shaft for rotating said disc. 105

5. A routing machine comprising a shaft and a rod extending in parallel relation one 105 to the other, a support for a routing disc pivoted upon said shaft and slidably longitudinally on said rod and shaft, said support being formed with an arcuate slot adapted to receive said rod, means on said rod adapted to engage said support, a routing disc 110 revoluble upon said support, and means operatively connected to said shaft for rotating said disc therefrom. 115

6. A routing machine comprising, a frame, 115 a horizontal shaft and a threaded rod extending in parallel relation one to the other in said frame, a series of supports for routing discs severally pivoted upon said shaft and formed with arcuate slots adapted to receive said rod, nuts threaded on said rod and arranged to engage opposite sides of said supports, a routing disc revoluble upon each of said supports, driving means severally connecting said shaft to said discs and a feed carriage adapted to deliver a stack of carton blanks to said discs. 120 125

In testimony whereof I have hereunto signed my name to this specification.

NELS SANDBERG.
